Attorney

UNITED STATES PATENT OFFICE.

JUDSON COOK, OF ALBANY, NEW YORK.

BRAKE-SHOE.

1,275,853.

Specification of Letters Patent. Patented Aug. 13, 1918.

Application filed October 25, 1917. Serial No. 198,530.

To all whom it may concern:

Be it known that I, JUDSON COOK, a citizen of the United States, residing at Albany, in the county of Albany and State of New York, have invented certain new and useful Improvements in Brake-Shoes, of which the following is a specification.

The object of the invention is the provision of a brake shoe having a body or tread 10 of cast metal reinforced by a wrought metal or steel back to which the key lug is secured, the key lug to be fashioned from a blank cut and bent to shape and interlocking with the back and held in part by the metal of the 15 body portion.

The invention consists in certain novelties of construction and combinations of parts as hereinafter set forth and claimed.

The accompanying drawing illustrates one 20 embodiment of the invention constructed and the parts combined according to the best mode of procedure I have so far devised for the purpose.

In the drawing,

25 Figure 1 is a vertical longitudinal section in elevation of the entire shoe.

Fig. 2 is a cross section of Fig. 1 taken on the line 2—2.

Fig. 3 is a top plan view of the reinforcing 30 plate.

Fig. 4 is a section of the plate taken on the line 4—4 of Fig. 3, and

Fig. 5 is a view in perspective of the key 35 lug detached from the plate and reversed to show the parts more clearly.

The shoe is comprised of the cast metal tread or body portion A, the wrought metal or steel reinforcing back B, and the steel key lug C.

40 The reinforcing back has two recesses 1, 1, formed by removing parts of the metal, two slots 2, 2, and two anchoring lugs 3, 3, each made by cutting two spaced holes 4, 4, from the metal and depressing the metal between the holes so as to lie in a plane or space below the surface of the back, as clearly shown by Figs. 3 and 4.

50 The key lug is made from a single rectangular steel blank by cutting away parts of the metal and bending other parts to provide a back or top 5, two sides 6, 6, with an opening 7, in each side for the passage of a key, four base portions, 8, 8, 8, 8, and four attaching wings 9, 9, 9, 9.

The wings are passed through the slots 55 2, 2, and the ends thereof then bent outwardly toward the recesses 1, 1, in the edges of the reinforcing back so they will lie in frictional contact with the bottom surface of the plate as clearly shown in Fig. 2. 60

Obviously two of the wings are passed through each slot 2, and when bent they lie in planes parallel with the base portions 8, 8, and securely anchor the key lug as a whole to the reinforcing back. 65

The back is then bent to an arched shape preparatory to its union with the body of the shoe. The ends of the reinforcing back and the metal bounding the recesses 1, 1, are fashioned to present beveled edges 70 10 and 11 over which edges the cast metal extends to more securely unite the back and the body of the shoe. The cast metal also fills the recesses 2, 2, as shown at 12, 12, in Fig. 2, and likewise extends through the 75 holes 4, 4, and over the top surface of the anchoring lugs 3, 3, as shown by Fig. 1, in section.

With the parts thus securely united a durable and efficient shoe is provided, which is 80 relatively cheap and simple in construction, easily made and consequently inexpensive in first cost.

Having thus fully described my invention what I claim and desire to secure by Letters Patent is,

1. A brake-shoe comprising a cast metal body or tread, a reinforcing back provided with slots centrally and longitudinally thereof, a key-lug being substantially box-shaped in form consisting of a back, side members projecting therefrom, and provided with registering openings therein, the extreme ends of said side members bent inwardly toward each other forming substantially a rectangular frame at opposite ends of the back, and locking-wings extending laterally from the extreme ends of the side members and inwardly toward each other and adapted to be received in the slots in the 90 reinforcing members, and having their ends bent and rigidly held by the metal of the body or tread portion. 95

2. A brake-shoe comprising a cast-metal body or tread, and reinforcing back provided with anchoring lugs seated in the cast metal and having slots, a key-lug being substantially box-shaped in form consisting of 100 105

a back, side-members projecting therefrom and provided with registering openings therein, the extreme ends of said side members bent inwardly toward each other, forming substantially a rectangular frame at opposite ends of the back, and locking-wings extending laterally from the extreme ends

of the side members and inwardly toward each other and adapted to be received in the slots in the reinforcing members, and having ¹⁰ their ends bent and rigidly held by the metal of the body or tread portion.

In testimony whereof I affix my signature.

JUDSON COOK.
